Primary Examiner — Justin M Jonaitis*Assistant Examiner* — Samantha K Pollack(57) **CLAIM**

The ornamental design for a knee phototherapy wrap, as shown and described.

DESCRIPTION

FIG. 1 is a perspective view of a knee phototherapy wrap in a folded position showing my new design.

FIG. 2 is a perspective view thereof shown in an unfolded position.

FIG. 3 is a front view thereof.

FIG. 4 is a rear view thereof.

FIG. 5 is a left side view thereof.

FIG. 6 is a right side view thereof.

FIG. 7 is a top view thereof; and

FIG. 8 is a bottom view thereof; and,

FIG. 9 is an enlarged view of the broken line circle shown in FIG. 3.

The broken lines in the drawings illustrate stitching and form no part of the claimed design. The broken line circles shown define the bounds of the enlargement and form no part of the claimed design.
